RETRACTABLE LINE APPLIANCE

John Odell Johnston, Irvington, N. J.

Application May 3, 1944, Serial No. 533,965

3 Claims. (Cl. 211—119.08)

This invention relates to a line appliance adapted for use by housewives in the hanging of clothes, and for similar uses.

It is customary to string clotheslines between a pole, located at some distance from the house proper, to a point adjacent the outside of the window casing, the clothesline being passed around pulleys located at the points mentioned. It is thus necessary for the user to lean partly out of the window casing for access to the clothesline, a procedure which is at once dangerous and awkward.

It is the object of my invention to provide a clothesline appliance whereby the user may attach clothes to the line or remove the same therefrom while remaining within the comfort and security of the inside of the house.

A further object of my invention is to provide a device of this character which is adapted to be fixed at one position in substantially the plane and axis of the clothesline proper for use of the clothesline, and is adapted to be fixed in another position at substantially right angles thereto when the clothesline is not to be used. In the latter position, the appliance is out of the way and does not in any manner interfere with the opening and closing of the windows of the casing through which the line passes in the use of the device.

A further object of the invention is to provide a device of this character which is adapted to be manufactured at low cost, and consists of few and simple parts, which are positive in operation, simple in construction and durable in use.

These and other advantageous objects, which will later appear, are accomplished by the simple and practical construction and arrangement of parts hereinafter described, and exhibited in the accompanying drawings, forming part hereof, and in which:

Fig. 1 is a fragmentary side elevational view of one form of the invention in its operative position.

Fig. 2 is a view on a similar plane of the device in its inoperative position.

Fig. 3 is a vertical transverse sectional view taken on line 3—3 of Fig. 2 in the direction of the arrows.

Fig. 4 is a vertical transverse sectional view taken on line 4—4 of Fig. 1 in the direction of the arrows.

Fig. 5 is a fragmentary elevational view of another form of the invention, taken on lines 5—5 of Fig. 6, in the direction of the arrows, and

Fig. 6 is a top plan view on a reduced scale of the structure shown in Fig. 5.

As shown in the drawings, the device consists of a bar 10, provided at one end (see Fig. 3) with a head 11 having a centrally disposed tapered portion 12 complementary to the tapered base member 14, the latter being secured to a suitable support, or to a bracket 15 which, in turn, is secured to the support such as the casing C, by means of screws 16 or the like. The device is thus rotatably disposed on the base for a purpose presently explained. A stud 17 is fixed by ring 13, or by welding or similar means to the bracket 15 or other support and protrudes therefrom at right angles thereto. A disc member 18 is positioned on the head 11, and a disc member 19, provided with centrally arranged offset boss 20 adapted to abut the disc member 18, is positioned on the latter. The disc members 18 and 19 are provided with oppositely flared peripheral portions which define a rope guide channel 29 for a purpose presently more fully explained. A spring 21 is seated within the offset portion 20 of the disc 19, the other end of the spring bearing against a cover plate 22 welded or otherwise secured to the latch member 30. The various parts described, namely, the tapered portion 14 of the base, the tapered portion 12 of the head 11, the disc 18, the offset portion 20 of the disc 19, and the cover plate 22, are provided with centrally arranged apertures to receive the stud member 17, the cross sectional diameter of the spring 21 being ample to freely receive said stud member. To hold the parts in predetermined position on the base 14, and for the operation of the device in the manner more particularly set forth hereinafter, a latch member 30 is provided, said latch member having a lever 31 by which it may be conveniently rotated and being internally threaded at 32 for engagement with the externally threaded end 33 of the stud 17.

The opposite end of the bar 10 is provided with a bracket portion 34 in which the axle 35 of the pulley 36 is journalled. The bracket 15 on which the device is mounted as above set forth is secured to the outer face of window casing C in alignment with the window opening O, (see Fig. 2). In order to use the device for hanging clothes or for "taking in" a clothesline, the bar 10 is rotated to a position in which it projects inwardly through the window opening O in the horizontal plane and axis of the clothesline proper (Fig. 1). In this position, the clothesline L passes from the remote pulley at the clothesline pole (not shown) through the window casing, tangentially through

the channel 29, around the pulley 36, and at a tangentially diametrically opposed point through the channel 29 and back to the pole pulley. As the pulley 36 is well inside of the house, the person using the line is in a convenient and safe position at all times in using the device. To latch the bar in this position, it is merely necessary to rotate the lever 31 of the latch 30 to thread the same on stud 17 whereby the various parts will be clamped between the cover plate 22 and base 14, the tapered portion 12 of the head 11 having complementary frictional engagement with the tapered portion of the base 14 for this purpose. The parts are left in that position until the user has finished using the line, at which time it is merely necessary to rotate the lever in the opposite direction to release the parts and the bar 10 may be moved downwardly at right angles to its previously described position, through the window opening O and outside the house in a vertical plane as shown in Fig. 2. Before dropping the bar 10 to this position, the line is lifted out of its lower tangent position in the channel 29 and is positioned at the upper tangent position in the channel so that both portions of the line are around the pulley and in the upper tangent position in the channel 29, as shown in Fig. 2. There is thus provided the fulcrum effect of a weighted end 37 which will effectively tend to resist movement thereof through opening O of the window casing until such time as it is desired to manually do so for the purpose of using the line. In the construction shown in Figs. 5 and 6 the axis A of the stud 17 is disposed in a vertical plane (see Fig. 5) instead of in the horizontal plane shown in Fig. 1 and the bracket member (see Fig. 5) is disposed in a horizontal plane, with an angularly disposed portion 38 which is adapted to be secured adjacent the casing opening at the outside of the house. In this form of the invention the bar 10 is moved inwardly in a horizontal plane for use of the device (full lines Fig. 6) and moved outwardly, also in a horizontal plane, but at right angles to its position of use and into a position across the opening O when it is not desired to use the same (dotted lines Fig. 6).

In the construction shown in Figs. 5 and 6, the bracket 34 is disposed at right angles to the plane of the base 14, the bar 10 being twisted and offset as at 39, for this purpose and to offset the bracket 34 so that, as shown in Fig. 5, the rope L passes from the pole pulley (not shown) tangentially through the channel 29, around the pulley 36 and downwardly out of the pulley and back to the pole pulley. When the user has finished using the line, the return portion of the line passing downwardly from the pulley 36 is lifted and positioned at the tangent position in the channel 29 adjacent the other portion of the rope, so that both portions of the line are around the pulley 36 and in the one

5 tangent position in the channel 29 shown in dotted portion of Fig. 6. The latching of the structure of Figs. 5 and 6 is like that described in connection with the structure of Figs. 1 and 2. Like parts are correspondingly numbered in the several figures of the drawings, for the sake of a more facile understanding of the invention.

10 While I have particularly described my invention as used in connection with clotheslines, it is equally applicable to any other application for use in connection with ropes, cables or the like wherein the structure described may be used to advantage. The parts described may be made of any desired or convenient metal, alloy or plastic.

15 Having thus described my invention, what I claim as new and desire to secure by Letters Patent is:

20 1. In a retractable line appliance, a bracket, a stud fixed to said bracket, a disc positioned on said stud, a second disc member positioned on said stud and provided with a centrally arranged offset boss adapted to abut the first mentioned disc member, said disc members being provided with oppositely flared peripheral portions which define a rope guide channel, a spring seated within said offset portion of the disc member, a latch member, a lever on said latch member, said latch member and said stud having complementary engaging means to latch the parts when the latch member is rotated in one direction and to release said parts when it is rotated in the opposite direction.

25 30 35 2. In a retractable line appliance, a bracket, a stud fixed to said bracket, discs positioned on said stud provided with oppositely flared peripheral portions and one disc having an offset portion which defines a rope guide channel, a latch member, a cover plate secured thereto, and a spring seated intermediate the disc members and cover plate, said latch member and said stud having complementary engaging means to latch the parts when the latch member is rotated in one direction and to release said parts when it is rotated in the opposite direction.

40 45 50 55 3. In a retractable line appliance, a bracket, a stud fixed to said bracket, discs positioned on said stud and provided with oppositely flared peripheral portions and one disc having an offset portion which defines a rope guide channel, a latch member and cover plate on said stud, a spring seated intermediate the disc members and cover plate, a bar in said appliance rotatably mounted at one end on said stud, and a pulley rotatably journaled on the opposite end of said bar, said latch member and stud having means to latch the bar against rotation on the stud.

JOHN ODELL JOHNSTON.
